UNITED STATES PATENT OFFICE.

GEORGE A. MEAD, OF MANSFIELD, OHIO, ASSIGNOR TO THE OHIO BRASS COMPANY, OF MANSFIELD, OHIO, A CORPORATION OF NEW JERSEY.

TROLLEY-WIRE CLAMP.

1,354,503.

Specification of Letters Patent.

Patented Oct. 5, 1920.

Application filed April 7, 1919. Serial No. 288,059.

To all whom it may concern:

Be it known that I, GEORGE A. MEAD, a citizen of the United States, residing at Mansfield, in the county of Richland and 5 State of Ohio, have invented certain new and useful Improvements in Trolley-Wire Clamps, of which the following is a specification.

This invention relates to trolley wire 10 clamps, the purpose of which is to securely support or suspend the trolley wire from its overhead support.

The object of the invention is to provide 15 means to hold the various parts in a yielding relation to each other whereby the looseness of the parts will not permit of rattle and whereby the trolley wire may be preliminarily secured within the clamping jaws prior to the clamp being rigidly secured in 20 a permanent position with respect to the overhead support or hanger.

The invention consists in the features of 25 novelty disclosed in the construction, combination and arrangement of the several parts shown in the accompanying drawings and disclosed in the specification, but more particularly pointed out in the appended claims.

Referring to the drawings:—

Figure 1 is an end view of the clamp in 30 partial section and shows the relation of the parts, before application to a hanger.

Fig. 2 shows an end view of the trolley 35 clamp in section and shows more clearly the same relation of the parts as in Fig. 1 and at the same time shows the relation of the clamp to the face of the hanger before the trolley wire has been inserted between the jaws.

Fig. 3 shows a sectional view of the clamp 40 and hanger and shows the relation of the parts not only of the clamp but their relation to the hanger when the parts of the clamp have been manipulated to permit the insertion of the trolley wire.

Fig. 4 is a sectional view of the clamp and hanger showing the trolley wire in place and 45 permanently secured there for operation.

Fig. 5 shows a side elevation view of the 50 clamp and hanger in section on the line 5—5 of Fig. 4.

Fig. 6 is a section view on the line 6—6 of Fig. 1 to show the interlocking of the two rotatable members.

The manufacturer of trolley clamps finds 55 it necessary on account of the great variety

of styles and sizes of trolley wire to minimize the varieties or sizes of trolley clamps as much as possible, not only from his own standpoint of reducing cost through reducing the number of styles or sizes of clamps 60 but from the standpoint of the user who very much prefers one clamp to meet all conditions if possible. To fulfil these requirements the manufacturer finds he is compelled to design his clamp in such a 65 manner that there is considerable looseness or variation in the parts in order that they may be adaptable to the various sizes of wire and this means that there is considerable rattle and movement of the parts relatively 70 to each other before they are installed. This has been found to detract from the impression which the clamps give the user and is liable to cause prejudice upon his part. With my improvement this objection is 75 overcome in a very simple manner as it tends to hold the parts in a somewhat fixed yet yieldable relation to each other when desired. This improvement also permits of attaching the hanger and clamp in position 80 and then stringing the trolley wire and slipping the same in place prior to the permanent securing of the clamp and trolley wire in final position. This is found to be 85 of advantage where the customer desires to string a considerable length of trolley wire and hold it up to position and then draw the same up taut before clamping the trolley wire in place.

In constructing my preferred form I provide a pair of clamping jaws indicated by the numeral 1 and these are held in a hinged relation to each other by means of the pin 2 passing through the lug 3 integrally secured to each of the jaws 1 and alternately related in the assembled device. The jaws are provided with a recess 4. In order to suspend the jaws and secure them to the overhead support I provide a rotatable stud 5 which is provided with a head or flange 6 and this head or flange I position in the groove or recess 4 of the jaws so that it will bear against the shoulder 7. The stud 5 is also provided with the hollow cylindrical part 8 which is internally screw threaded for engagement with the stud of the overhead support. The cylindrical member 8 is provided with the flange 9 the periphery of which is provided with a plurality of faces. Surrounding the stud 5 is a collar 10, the 100 105 110

lower outer edge of which is beveled as indicated at 11 and this beveled edge 11 engages the corresponding beveled face 12 on the inner face of the jaws 1. The collar 10 is provided with the shoulder 13 and positioned between the shoulder 13 and the flange 9 is a spring 14 tending to press the shoulders 9 and 13 apart and consequently the members to which these shoulders are attached. This tendency of the members 5 and 10 to be moved as described causes the upper portion of the jaws 1 to be moved outward and with sufficient spring action the jaws will be moved as far as their construction will permit and hence the parts will be held in a yielding but firm relation relatively to each other.

The inner face of the collar 10 is provided with a plurality of faces coinciding with the faces on the last line, all as shown in Fig. 6. The outer face of the collar 10 is also provided with a plurality of faces for the application of a wrench which is necessary when permanently installing the clamp upon a hanger to cause it to securely grip the trolley wire. When the member 10 is rotated the stud 5 is likewise rotated on account of the plurality of engaging faces.

In installing the device just described the clamp is screwed onto the supporting stud 15, leaving however a space between the lower face of the hanger 16 and the upper face of the collar 10 as indicated by A. The upper portion of the jaws 1 are then squeezed together thereby forcing the collar 10 upward against the tension of the spring 14 as shown in Fig. 3 and this opens the lower edge of the jaws 1, permitting the insertion of the trolley wire. When the trolley wire has been thus inserted, the jaws are allowed to spring back thereby engaging the trolley wire under the action of the spring 14. A wrench is now applied to the collar 10 and the rotation of the collar 10 will cause the stud 5 to be rotated and this will draw the stud 5 into further engagement with the stud 15 and this rotation is continued until the upper face of the collar 10 is in firm engagement with the face of the hanger 16 and further rotation of the stud 10 will then draw the jaws and stud 5 upwardly, causing the jaws to move relatively to the collar 10, thereby forcing the upper edges of the jaws outwardly and the lower edges of the jaws into firm and secure engagement with the trolley wire, thus

completing the installation of the clamp and wire.

I am aware that the herein disclosure will suggest variations that may be made, to those skilled in the art, but I do not wish to be limited as to the scope of my invention beyond that set forth in the appended claims.

65
What I claim is:—

1. A trolley wire support comprising clamping jaws adapted to receive and clamp a trolley wire, a member rotatably secured to the jaws and having means for attachment to a hanger, means movable relatively to the jaws to move them into secure engagement with the trolley wire and yielding means acting on the last named means for maintaining the parts in yieldable engagement with each other prior to being secured to the trolley wire hanger.

70
2. A trolley wire clamp comprising in combination a pair of clamping jaws adapted to engage and hold a trolley wire, a rotatable member engaging the jaws and having means for engaging a support, an operating member mounted on and rotatable with the rotatable member to secure the jaws in permanent clamping engagement 75 with the trolley wire and yielding means interposed between the members to hold the operating member in yielding engagement with the jaws.

80
3. A trolley wire clamp comprising in combination a pair of clamping jaws adapted to engage and hold a trolley wire, a rotatable member engaging the jaws, an operating member mounted on, rotatable with and movable longitudinally of the rotatable 85 member to secure the jaws in permanent clamping engagement with the trolley wire and yielding means interposed between the members to move them relatively to each other in one direction longitudinally.

90
4. A trolley wire clamp comprising a pair of clamping jaws adapted to engage and hold a trolley wire, a support member engaging the jaws and provided with means 95 for engagement with a support, an operating member mounted on the support member to engage the jaws and maintain them in engagement with the trolley wire, and resilient means engaging the operating means to maintain it in yielding engagement with the trolley wire.

100
In testimony whereof I affix my signature.

105
GEORGE A. MEAD.
